CLAIM

The ornamental design for a water barrier trim, as shown and described.

DESCRIPTION

FIG. 1 is a right side view of our water barrier trim, the left side view being a mirror image thereof;

FIG. 2 is a front view thereof;

FIG. 3 is a rear view thereof;

FIG. 4 is a top view thereof;

FIG. 5 is a bottom view thereof; and,

FIG. 6 is a perspective view thereof.

In FIGS. 2 through 6 the water barrier trim is cut to indicate that the water barrier trim can be of any length.
